COMBINED GARBAGE COOKER AND DRIER

Filed June 16, 1930

UNITED STATES PATENT OFFICE

WILBUR A. KRAMER, OF DAYTON, OHIO, ASSIGNOR TO THE ADVANCE FOUNDRY COMPANY, OF DAYTON, OHIO, A CORPORATION OF OHIO

COMBINED GARBAGE COOKER AND DRIER

Application filed June 16, 1930. Serial No. 461,295.

This invention relates to new and useful improvements in combination garbage cookers and dryers.

It is one of the principal objects of my invention to provide an economical and durable steam-jacketed pressure vessel such as a garbage cooker and dryer.

Another object of my invention is to provide for the cooker, a bottom member which, being one casting, will present no seams and holes for abrasive action due to the agitation of the garbage.

It is another object of my invention to provide a multiplicity of steam passages connected together by manifold means to remove the hazard of a single high pressure steam compartment.

In the accompanying drawing illustrating my invention, Figure 1 is a longitudinal, sectional view taken through my pressure vessel. Figure 2 is a cross sectional view taken through the bottom portion of the same, showing the agitator. Figure 3 is a top view of the vessel. And Figure 4 is a sectional view taken through the steam jacket on the line 4—4 of Figure 2, showing how the bracing ties and ribs are constructed and arranged to permit the circulation of steam.

Referring to the accompanying drawing illustrating my invention, the numeral 1 designates a pressure vessel made up of a bottom casting 2, an intermediate casting 3, a top casting 4, a cover plate 5, a filler neck 5^a and a charging door 6.

Formed on the bottom portion of the casting 2 are flanged feet 7 which rests upon posts 8 for support above a motor 9. Through a worm drive (not shown) in a casing 10 supported by feet 11, the motor 9 rotates a vertical shaft 12 that projects through a hole 13 in the bottom of the casting 2. Attached to the shaft 12 within the casting 2 is a horizontal propeller or agitator 14.

Fitted in the hole 13 in the bottom of the casting 2 is a bearing 15 for the shaft 12. This bearing has a bottom flange 16 that is secured by bolts 17 to the casting. Surrounding the shaft 12 within the enlarged lower portion of the bearing is a packing 18 that

is held in place by a gland 19 carried by the bearing.

Formed in the bottom of the casting 2 around its central portion 13 is an annular steam jacket or space 20 with which an extension 21 on the lower end of a steam inlet manifold 22 communicates.

The bottom section 2 of the vessel 1 has a double side wall to provide communicating steam spaces 23 between bracing ties 24. These spaces are divided by ribs 25 containing apertures 26 through which the steam circulates. To the communicating spaces 23 in the casting 2 steam is admitted from a radial connection 26^a on the manifold 22.

The intermediate section 3 of the vessel 1 is also provided with a double wall to form communicating steam spaces 27 between bracing ties 28. These spaces are divided by ribs 29 containing apertures 30 for the circulation of the steam. To these spaces 27 steam is introduced by a radial connection 31 on the inlet manifold 22.

Steam introduced from a source not shown through the manifold 22 into the jacketed sides of the section 3 and the section 2, and to the jacketed bottom of the latter, serves to cook the agitated garbage within the vessel.

In order that it may be firmly secured to the section 3, the section 2 is formed with an apertured top flange 32 to receive studs 33 that enter tapped holes in the bottom of the section 3. Into tapped holes in the top portion of the latter section studs 34 are inserted after being passed through holes in a flange 35 on the bottom of the top section 4 to firmly secure it to the section 3.

The cover plate 5 is flanged for connection to the flanged top of the casting section 4 by bolts 36. Over an opening 37 in this cover plate the filler neck 5^a is attached by means of studs 38. Pivots secured to fixed arms 39, 39 on one side of the filler neck, by a hinge pin 40, are two hinge members 41, 41 integral at their inner ends with the top of the circular charging door 6. This door is held closed by clamping bolts 42 hingedly secured at their lower ends to fixed ears 43 on the filler neck.

The steam jackets in the sealed cooker just

described are separated to reduce the capacity of each compartment to meet the requirements of various safety codes for high pressure steam vessels.

5 Steam arising from the cooking garbage leaves the filler neck 5^a through an opening 44 in the latter. Condensed steam from the jacketed portions of the casting sections 2 and 3 is discharged through a drain tube 45
10 which communicates with the steam passages 27 through a radial connection 46, with the steam passages 23 through a radial connection 47 and with the bottom steam space 20 through a connection 48. A pet cock air
15 vent 49 is also connected to the steam jacketed side wall of each one of the casting sections 2 and 3, and to the bottom of the section 2.

Formed in the lower part of the double
20 wall of the casting section 2 is a clean out
25 opening 50 closed by a hinged door 51 that
is U-shaped in cross section. This door,
which is adapted to be held closed by bolts
25, carries a test valve 53 within its recessed
portion. Through this valve a specimen of
the cooked garbage may be removed for
testing.

Having described my invention, I claim:
30 A garbage cooker and dryer comprising
a sectional cylindrical casting having double
walls to provide steam compartments, ties
between said walls, ribs also between said
35 walls, said ribs being formed with holes to
pass the steam from one compartment to the
other, a steam line for introducing steam to
said compartments, and an outlet line for
the condensed steam in said compartments.

In testimony whereof I have hereunto set
my hand this 13th day of June, 1930.

40 WILBUR A. KRAMER.
